UNITED STATES PATENT OFFICE.

FRANK COLLINS, OF NEW YORK, N. Y., ASSIGNOR TO MUTUAL SUNSET LAMP MFG. CO. INC., OF NEW YORK, N. Y., A CORPORATION OF NEW YORK.

DESIGN FOR A LAMP ARM

Application filed July 9, 1926. Serial No. 18,284. Term of patent 3½ years.

To all whom it may concern:

Be it known that I, FRANK COLLINS, a citizen of the United States, residing at New York, in the county of New York and State of New York, have invented a new, original, and ornamental Design for a Lamp Arm, of which the following is a specification, reference being had to the accompanying drawing, forming part thereof.

The accompanying drawing represents a side elevation of my improved lamp arm.

I claim:

The ornamental design for a lamp arm, as shown.

FRANK COLLINS.
